UNITED STATES PATENT OFFICE.

JAMES DE CATOR, OF LOCK HAVEN, PENNSYLVANIA.

RAILROAD-TIE CONSTRUCTION.

Application filed January 29, 1926. Serial No. 84,707.

This invention relates to rail securing means and has for an object the provision of means whereby car rails may be quickly and securely attached to a tie in a manner to hold the said rails in proper position, yet permit of expansion and contraction.

Another object of the invention is the provision of means of this character which may be quickly adjusted for use and may be conveniently arranged for storage or shipment.

Another object of the invention is the provision of rail securing means which are simple in construction, reliable in use and which may be readily adjusted to a rail and tie.

With the above and other objects in view, the invention further includes the following novel features and details of construction, to be hereinafter more fully described, illustrated the accompanying drawings and pointed out in the appended claims.

In the drawings:—

Figure 1 is a fragmentary transverse sectional view illustrating the invention in use.

Figure 2 is a top plan view of the same.

Figure 3 is a section taken substantially on the line 3—3 of Figure 1.

Figure 4 is a plan view of the rail plate.

Figure 5 is a similar view of one of the tie pockets removed from the tie.

Figure 6 is a section on the line 6—6 of Figure 5.

Figure 7 is a plan view of one of the clamping members.

Figure 8 is a fragmentary plan view of a portion of the tie showing one of the openings therein.

Figure 9 is a side elevation of one of the clamping members.

Referring to the drawings in detail wherein like characters of reference denote corresponding parts, the tie, a portion of which is indicated at 15 is preferably of the hollow metal type and is designed to support the rails, one of which is indicated at R.

Upon opposite sides of each rail R, the tie is provided with longitudinally disposed openings 16, these openings receiving ribs 17 which extend downwardly from clamping members 18 and 19. The clamping member 19 is provided with an upwardly inclined extension 20 which is adapted to enter the fishing space upon the outside of

the rail, while the clamping member 18 is provided with an extension 21 which extends over the base flange upon the inner side of the rail. By reference to Figure 1 of the drawings it will be seen that sufficient clearance between the extensions 20 and 21 and the rail R is provided to permit of expansion and contraction, while the manner of engagement between the clamping members and rail is such as to hold the latter in proper position. It is preferred to provide a rail plate 22 beneath the rail. This plate may be formed of fiber or other suitable material and acts as a rail cushion, insulator and anti-friction member so that the rail may be slid longitudinally from its position between the clamping members.

Clamping members 18 and 19 are designed to be secured to the ties between the angle bars B and in order to secure the rails to the ties at the rail joints there are provided clamping members 23, one of which is shown in detail in Figure 9 of the drawings. These clamping members 23 differ from the clamping members 18 and 19 only with respect to the extensions 24 which extend upwardly over the flanges of the angle bars B.

Secured beneath the openings 16 of the tie 15 are pockets 25, the latter being provided with apertured ears 26 by means of which they may be riveted or otherwise secured to the ties as indicated at 27. Extending inwardly from opposite walls of the pockets 25 are bearing sockets 28. These sockets receive pintles 29 which extend from opposite sides of the inner ends of arms 30, the pintles extending beyond the opposite side edges of the openings 16 beneath the lower face of the tie so as to securely hold the pintles within the sockets. The arms 30 have their inner ends pivotally secured within the pockets 25 so that they may be swung downward within said pockets to an out of the way position when the tie is not in use. The outer ends of the arms 30 and one end of the pockets 25 are beveled as indicated at 31 and 32 respectively so that when the arms occupy a position within the pockets, a suitable tool may be inserted between these beveled portions for conveniently raising the arms.

In use, the arms extend upwardly through openings 33 provided in the clamping members and are provided with transversely arranged openings 34, one wall of which is

beveled as shown at 35. These openings 34 receive wedges 36 which are adapted to be driven into position to tightly clamp the members 18 and 19 and 23 in position and hold them against vertical movement; while engagement of the ribs 17 with the walls of the openings 16 prevents horizontal movement. The wedges 36 are provided with openings 37 for the reception of locking pins 38.

The invention is susceptible of various changes in its form, proportions and minor details of construction and the right is herein reserved to make such changes as properly fall within the scope of the appended claims.

Having described the invention what is claimed is:—

1. Rail fastening means comprising in combination with a tie having openings upon opposite sides of the rails, clamping members upon opposite sides of the rails and engaging the tie and rails, said members having openings therethrough, arms extending through the openings of the clamping mem-

bers and tie, means for pivotally securing the inner ends of the arms to the tie whereby the arms may be swung downward within the tie openings and adjustable means carried by the arms and engaging the clamping members.

2. Rail fastening means comprising in combination with a tie having openings upon opposite sides of the rails, clamping members upon opposite sides of the rails and engaging the tie and rails, said members having openings therethrough, arms extending through the openings of the clamping members and tie, a pocket extending downwardly beneath each tie opening, bearing sockets provided in opposite side walls of the pockets, pintles extending from the inner ends of the arms into the bearing sockets whereby the arms will be pivotally secured to the tie and adjustable means carried by the arms and engaging the clamping mem-

In testimony whereof I affix my signature.
JAMES DE CATUR.
